C. Snow & Co.

UNITED STATES PATENT OFFICE.

JOHN W. RATCLIFF, OF WEBBVILLE, KENTUCKY.

CULTIVATOR.

SPECIFICATION forming part of Letters Patent No. 616,971, dated January 3, 1899.

Application filed April 25, 1898. Serial No. 678,800. (No model.)

To all whom it may concern:

Be it known that I, JOHN W. RATCLIFF, a citizen of the United States, residing at Webbville, in the county of Lawrence and State of Kentucky, have invented a new and useful Cultivator, of which the following is a specification.

This invention relates to agricultural implements embodying in their construction a fixed beam, to which the handles and draft are applied, and a laterally-shiftable beam having pivotal connection with the fixed beam, whereby furrows may be formed at any required distance apart within the limit of range of movement of the adjustable beam.

The purpose of the invention is to improve the construction of this class of implements and admit of the shiftable beam being moved from one side to the other of the fixed beam, to simplify the construction, and to provide an implement which will be strong, lasting, and capable of being easily managed and drawn over the field by the application of a comparatively light draft.

For a full understanding of the merits and advantages of the invention reference is to be had to the accompanying drawings and the following description.

The improvement is susceptible of various changes in the form, proportion, and the minor details of construction without departing from the principle or sacrificing any of the advantages thereof, and to a full disclosure of the invention an adaptation thereof is shown in the accompanying drawings, in which—

Figure 1 is a side elevation of a plow constructed in accordance with this invention. Fig. 2 is a top plan view, the dotted lines showing the movable plow-beam shifted from one side of the implement to the other. Fig. 3 is a rear view. Fig. 4 is a detail section of the cross-piece, showing the relation of the movable plow-beam.

Corresponding and like parts are referred to in the following description and indicated in the several views of the drawings by the same reference characters.

The fixed plow-beam 1 has its rear end curved, forming a standard 2, to which a plow-point of any desired make or pattern is secured. The front end portion of the beam 1

is reduced and bent back upon itself, forming a loop 3, to which the draft is applied. The handles 4 are secured to the beam 1 at a point 55 midway of its length and have their position fixed by braces 5, which are made fast at their lower ends to the rear portion of the beam 1 and incline upwardly and outwardly and are bolted at their upper ends to the handles intermediate of their ends.

A cross-piece 6 is rigidly attached at a middle point to the beam 1 and is formed with an arcuate slot 7. This cross-piece curves throughout its length to conform to the slot 65 7 and is depressed in its upper face, bordering upon the slot 7, so as to admit of the head portion of the bolt or fastening 8 coming below the plane of the top side of the cross-piece and not interfere with the beam 1. The beam 1 is let into the upper side of the cross-piece, and the latter is formed upon its rear portion with lugs 9, which embrace the sides of the beam 1 and serve to strengthen and brace the cross-piece and result in a firm and 75 rigid structure.

The shiftable beam 10 has pivotal connection at its front end with the beam 1, and its rear end portion is curved downwardly and receives a shovel or plow-point, according to 80 the nature of the soil and the condition of the work to be performed. The bolt 11, upon which the beam 10 turns, serves to connect the folded end of the beam 1 with the body portion thereof, and the cross-piece 6 and the 85 slot 7 thereof are formed on the arc of a circle having the bolt 11 as its center. The bolt or headed fastening 8, applied to the rear portion of the beam 10, operates in the slot 7 of the cross-piece 6 and serves to support the 90 rear end of the beam 10 and prevent relative upward movement of the beam 1. The beam 10 is of less length than the beam 1 and can be moved from one side of the main beam to the other, as indicated by the full and dotted 95 lines in Fig. 2, and can be adjusted to an intermediate point between the extreme movements, so as to cause the shovel or plow-points to track as close together or as far apart as required.

Suitable means are resorted to for securing the beam 10 in an adjusted position and consists of latch-plates 12, pivoted at their inner ends to the middle portion of the cross-piece

6 and having their outer ends reduced and bent laterally, forming stops 13, which overlap the cross-piece and limit the relative downward movement of the pivoted plates. 5 These plates have notches 14 in their lower edges to embrace the sides of the beam 10 and secure it against lateral movement when shifted to the required position. The outer ends of the plates terminate in shoulders 15, which 10 engage with the side of the beam 10 facing the beam 1, so as to prevent inward movement thereof, the outward movement of said beam being prevented by the headed fastening 8 engaging with the closed end of the slot 7. The sides of the beam 10 are indented, so as to be engaged by the shouldered portions of the pivoted plates 12, thereby guarding in a measure against vertical movement of the pivoted plates after the parts have 15 been adjusted. Lugs 16 are formed at the upper edges of the pivoted plates, and cords 17 connect therewith and pass through guide-eyes applied to the handles and cross-piece connecting the handles and extend within 20 convenient reach of the attendant, so as to be pulled upon to disengage either plate from the beam 10 when it is required to release it to admit of the said beam being shifted to a new or desired position. 25 Having thus described the invention, what is claimed as new, and desired to be secured by Letters Patent, is—

30 1. In an agricultural implement, the combination with a fixed plow-beam, and a shift- 35 able plow-beam movable laterally from one side to the other of the fixed beam, of a se- curing device for holding the shiftable beam in any of its adjusted positions, and separate releasing means for the securing device, said 40 means being mounted in normal reach of the operator, substantially as shown and de- scribed.

2. In an agricultural implement, the com- 45 bination with a fixed plow-beam, of a shift- able plow-beam movable laterally from one side to the other of the fixed beam, a secur- ing device for holding the shiftable beam in any of its adjusted positions, and separate 50 means for releasing the securing device, said means comprising a cord or like connection mounted in guides provided upon the handle of the implement and in normal reach of the operator, substantially as shown and de- scribed.

55 3. In an agricultural implement, the com- bination of a fixed plow-beam and a cross- piece applied to the fixed plow-beam and form- ing a guideway, of a shiftable plow-beam piv- otally connected at its front end to the for-

ward end of the fixed plow-beam, a positive 60 connection between the cross-piece and shift- able plow-beam, and a movable plate applied to the said cross-piece and constructed to make positive engagement with the shiftable plow-beam and secure it in the required ad- 65 justed position, substantially as set forth.

4. In an agricultural implement, the com- bination with a fixed plow-beam and a cross- piece applied to the fixed plow-beam and forming a guideway, of a shiftable plow-beam pivot- 70 ally connected at its front end to the forward end of the fixed plow-beam and having direct connection with the cross-piece, plates pivoted at one end to the cross-piece upon each side of the fixed plow-beam and adapted to 75 make positive connection with the shiftable plow-beam, and a connection applied to the pivoted plates for simultaneously operating them, substantially as set forth.

5. In combination, a plow-beam, a cross- 80 piece secured to the main plow-beam and having the latter let into its top side and braced by lugs of said cross-piece, a second plow-beam having pivotal connection at its 85 front end with the main plow-beam and adapt- ed to be swung horizontally beneath and from one side to the other of the main plow-beam, a headed fastening applied to the pivoted plow- beam and operating in a slot of the cross-piece, plates pivoted at their inner ends 90 to the cross-piece and having notches in their lower edges to engage with the pivoted plow- beam and secure it in an adjusted position, and connections applied to the pivoted plates for operating them, substantially as set forth. 95

6. In an agricultural implement, the com- bination of a fixed plow-beam, a shiftable plow-beam movable laterally from one side to the other of the fixed beam, a securing de- 100 vice in the form of a pair of latch-plates pro- vided upon opposite sides of the fixed beam and adapted to hold the shiftable beam in any of its adjusted positions, and separate 105 means for simultaneously operating both latch-plates, comprising a cord or suitable connection attached at its opposite ends to the respective latch-plates and mounted upon the handles of the implement in normal reach of the operator, substantially as shown and de- scribed.

In testimony that I claim the foregoing as my own I have hereto affixed my signature in the presence of two witnesses.

JOHN W. RATCLIFF.
